DEAD END CLAMP

L. E. Lindsey, 222 Vista Ave., Pasadena, Calif. 91007,
and Herbert F. Sammons, Glendale, Calif.; said Sammons
assignor to said Lindsey

Filed June 16, 1969, Ser. No. 17,726

Term of patent 14 years

Int. Cl. D8—03

U.S. Cl. D8—230

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is a top plan view of a dead end clamp embodying our new design according to one preferred species;

FIG. 2 is a side elevational view taken from the lower side of FIG. 1;

FIG. 3 is an end elevational view taken from the left-hand end of FIG. 2;

FIG. 4 is a bottom plan view of FIG. 1;

FIG. 5 is a side elevational view taken from the top side of FIG. 1;

FIG. 6 is an end view taken from the left-hand end of FIG. 5;

FIG. 7 is a top plan view of a dead end clamp embodying a second preferred species of our new design;

FIG. 8 is a side elevational view taken from the lower side of FIG. 7;

FIG. 9 is an end elevational view taken from the left-hand end of FIG. 2;

FIG. 10 is a bottom plan view taken from the bottom of FIG. 1;

FIG. 11 is a side elevational view taken from the upper side of FIG. 7; and

FIG. 12 is an end elevational view taken from the left-hand end of FIG. 11.

We claim:

The ornamental design for a dead end clamp, as shown and described.
